VENETIAN BLIND

Scipio S. Gentile, North College Hill, Ohio

Application April 29, 1942, Serial No. 446,939

10 Claims. (Cl. 160—236)

My invention relates to a new and improved slat construction for Venetian blinds, which is inexpensive, pleasing in appearance, and which will retain its form without sagging.

Venetian blind slats are usually made of wood or some other relatively heavy material, which requires painting and finishing and which is relatively expensive. On the other hand, Venetian blind slats have been made of paper or fiber or other inexpensive material, but due to the inherent nature of the material, there is a decided tendency for them to sag or otherwise become distorted, unless heavily reinforced, which, of course, adds to the expense of the slat.

It is an object of my invention to provide a light weight, inexpensive Venetian blind slat made of paper or thin fiber and so proportioned and arranged that it will maintain its shape and appearance.

These and other objects of my invention, which will be set forth hereinafter, or which will be apparent to one skilled in the art upon reading these specifications, I accomplish by that certain construction and arrangement of parts of which I shall now describe an exemplary embodiment. Reference is now made to the drawing which forms a part thereof and in which:

Figure 1 is a perspective view of a portion or section of my novel slat.

Figure 2 is an enlarged cross section of the edge portion of my slat, taken on the section line 2—2 of Figure 1.

Figure 3 is a cross section of a modified form of my novel slat.

Figure 4 is a cross section of another modification of my novel slat, wherein the upper portion is of heavier material than the lower portion.

Figure 5 is a modification of my novel slat, wherein the edges are folded over to increase rigidity of the slat.

Briefly in the practice of my invention I provide a Venetian blind slat formed of paper or other relatively thin but stiff material and having an upper and a lower face. The width or transverse section of the upper portion of my slat is greater than that of the lower portion, so that when their edges are secured together, the upper portion or face of the slat is arched or bowed, thus tending to stretch the lower face of the slat and thus through oppositely opposed forces to maintain the lower surface of the slat in a plane at all times. The margin or edge of the secured portions are reinforced to a more or less degree which also assists in maintaining the configuration of the slat.

Referring to the drawing:

Briefly, I provide a lower portion or face of the slat 1 of paper or other relatively thin material. Superimposed upon this portion I place an upper face or portion 2 and fold the protruding edges 3 of the portion 1 over the edges of the portion 2, and in so folding I shorten the cross section of the portion 1 to a less width than the portion 2, so as to bow up or arch the portion 2, as is clearly apparent in the drawing, Figures 1 and 2.

In the exemplary embodiment shown in Figures 1 and 2, I form a loop or bead 4 before folding the edge 3 of the lower portion 1 down upon the face of the upper portion 2 and securing the members together. The members may be secured by crimping, riveting, gluing, or by any other securing means well known in the art.

The resulting structure, as is apparent in Figures 1 and 2, consists of a Venetian blind slat, wherein the cross section consists of a bowed or arched upper surface and a flat lower surface. The lower surface 1 is kept under a stretching tension by the arching of the upper portion 2. The beading 4 on the edge also assists in maintaining the alignment and configuration of the slat.

In Figure 3, I have shown a modification wherein in the upper portion 2, besides being arched, has folders 6 formed therein. In this modification the edges 3 of the lower portion 1 are directly folded over the edges of the upper portion 2. By this construction the formed paper slat is given a thickness which makes it appear as if formed of wood or other heavy material. It is to be noted that in this modification the lower portion 1 is constantly maintained under stretching tension by the arched upper member 2.

The modification shown in Figure 4 is quite similar to that shown and described in Figures 1 and 2, excepting that the upper portion 2 is of heavier material than the lower portion 1, and thus the lower portion 1 is maintained under a greater stretching tension than would otherwise be the case. It is also to be noted that in this modification, no beading is provided on the edges, since the relatively heavy upper portion 2 is sufficiently stiff to maintain a straight edge.

The modification illustrated in Figure 5 is again similar to that in Figures 1 and 2, excepting that in this instance the upper and lower portions are of the same thickness and the edge of the upper portion is folded back upon itself before the edge 3 of the lower portion 1 is folded

over and secured, thus forming a strengthened edge.

It is to be understood that my novel Venetian blind slat is combined together in the usual manner of forming Venetian blinds. The appearance of the finished blind is extremely pleasing to the eye and quite sturdy. In some cases the material forming the slats may be slightly translucent and thus present pleasing and varying effects due to the transmission of light therethrough.

It is to be understood that different forms of my preferred form may be made without departing from the spirit of my invention.

Having thus described my invention, what I claim as new and desire to secure by Letters Patent is:

1. A slat for a Venetian blind comprising a pair of members assembled together, one of said members of greater width than the other member forming a hollow arched slat having a flat bottom or base.

2. A slat for a Venetian blind comprising a pair of members assembled together, one of said members of greater width than the other member forming a hollow arched slat, and a bead along the side margins of said slat having a flat bottom or base.

3. A slat for a Venetian blind comprising a flat base member, an arched upper member, and means for securing said members together.

4. A slat for a Venetian blind comprising a flat base member, an arched upper member, the margins of said base member folded over the margins of said upper member, and means for securing said members together.

5. A slat for a Venetian blind comprising a flat base member, and an arched upper member exerting a stretching tension on said base member.

6. A paper slat for a Venetian blind comprising a flat base member, an arched upper member, the margins of said base member folded over the margins of said arched member forming beads along the side margins of said slat, and means for securing said members together.

7. A paper slat for a Venetian blind comprising a flat base member, an arched upper member, the margins of said base member folded over the margins of said arched member, means for securing said members together, and said members spaced apart throughout the greater portion of their area.

8. A Venetian blind slat comprising a flat base member, an arched upper member, the margins of said upper member being folded and the margins of said base member being folded over the margins of said upper member, and means for securing said members together.

9. A Venetian blind slat comprising a flat base member, an arched upper member, and means for securing said members together, said arched upper member being of thicker material than said base member.

10. A Venetian blind slat comprising a flat base member, an upper member having upstanding walls and an arched top, and means for securing said members together.

SCIPIO S. GENTILE.
